UNITED STATES PATENT OFFICE

2,449,124

MUSICAL INSTRUMENT

Arthur Horden Kimmons, Burgettstown, Pa.

Application August 26, 1946, Serial No. 693,104

1 Claim. (Cl. 84—267)

1

This invention relates to a novel construction of string instruments adapted to be played by means of a pick or plectrum, and which is especially intended and adapted and capable of being played to produce an accurate rendition of musical airs, either employing the instrument for solo work or as an accompaniment to other instruments or as an instrumental accompaniment to solo, group or choir singing.

More particularly, it is an object of the invention to provide a novel construction of three-stringed musical instrument capable of being played with equal ease while noting the instrument with the left hand and picking strings with the right hand or while noting with the right hand and picking the strings with the left hand, to enable the instrument to be utilized with the same degree of ease by either right or left-handed persons and without changing or affecting the location or tuning of the strings.

Still a further aim of the invention is to provide an instrument having a novel arrangement of sound openings in the body thereof and by means of which the sound volume of the instrument will be considerably magnified.

Still a further aim of the invention is to provide an instrument of the aforescribed character of extremely simple yet durable construction and which is capable of being played in an accurate and pleasing manner with much less musical training and practice than is required for playing instruments of a similar character.

Various other objects and advantages of the invention will hereinafter become more fully apparent from the following description of the drawings, illustrating a preferred embodiment thereof, and wherein:

Figure 1 is a plan view of an instrument constructed in accordance with the invention;

Figures 2 and 3 are cross sectional views taken substantially along planes as indicated by the lines 2—2 and 3—3, respectively, of Figure 1;

Figure 4 is a longitudinal sectional view taken substantially along a plane as indicated by the line 4—4 of Figure 1;

Figure 5 is a fragmentary perspective view of the instrument, and

Figure 6 is a plan view of the pick or plectrum for use with the instrument.

Referring more specifically to the drawings, the musical instrument in its entirety is designated generally 7 and includes an elongated body 8 having a substantially flat top 9 and bottom 10 and a continuous curved side wall 11. The parts 9, 10 and 11 combine to form the body 8 which is

2

enlarged adjacent the tail end thereof and rounded at said end, and tapered gradually toward its opposite, neck end. The top wall 9 of the body 8, in the enlarged part thereof, is provided with two generally S-shaped sound openings 12, which are disposed lengthwise of the body, and the top wall 9 is also provided with a pair of circular openings 13 which are located between the openings 12, and the tapered, neck end of the body 8.

The instrument 7 is provided with a finger bar 14 which is disposed longitudinally and centrally thereof and above the top wall 9 and which extends from end to end of the body 8. As best illustrated in Figure 5, the finger board 14 is provided with depending end portions 15 and 16, which rest upon the top 9, adjacent the ends thereof, for supporting the intermediate, undercut portion 17 of the finger board 14 in spaced apart relationship to and over the body 8. Said intermediate portion 17 is provided, substantially intermediate of the ends of the finger board 14, with a depending, relatively narrow support 18, which extends transversely thereof and which rests on the top wall 9. The finger board 14 is provided with a plurality of frets 19 which project upwardly from the upper surface thereof, which are disposed transversely of the finger board and which are located thereon from adjacent the neck end of the finger board to point spaced from the tail-piece end thereof.

The end of the finger board, contiguous with the portion 16, forms a tail-piece 20 having fastenings 21 to which corresponding ends of three strings 22, 23 and 24 are fastened. The finger board portion 16 is provided with an upstanding transversely rounded part forming a bridge 25, which is located above the tail-piece 20 and which is provided with openings or grooves 26 for receiving and correctly positioning the strings 22, 23 and 24, adjacent to the ends thereof which are fixed to the fastenings 21. The finger board 14 is provided with an upstanding, transversely disposed bridge 27 located adjacent the opposite end thereof and beyond the uppermost fret 19; said bridge 27 being provided with grooves 28 for correctly positioning the strings 22, 23 and 24 thereon.

As best illustrated in Figures 4 and 5, the upper surface of the finger board 14 is provided with a longitudinally extending concave portion 29 which is disposed between the bridge 25 and the adjacent fret 19 and from which the strings are spaced a greater distance than from any other part of the finger board. As seen in Figure 4, the

upper surface of the finger board 14 is inclined upwardly and away from the upper surface of the body 8 from its recessed portion 29 to the portion thereof to which the bridge 27 is secured.

A neck 30 is secured to and projects from the narrow end of the body 8, beyond the finger board end 15 and is provided with three tuning or string keys 31 each including sections connected by a worm and worm gear and to which the opposite ends of the strings 22, 23 and 24 are adapted to be connected to permit said strings to be individually loosened or tightened and thereby tuned.

The two outer strings 22 and 24 are adapted to be tuned to the same note, to "B" and the center string is tuned to "G." In playing the instrument 7, as for example, by a right-handed person, the instrument may be placed across the lap with the neck 30 adjacent the left hand and the musician then employs his left hand for noting the strings between the frets 19, preferably by the use of a match stem. A pick or plectrum 32, as illustrated in Figure 6 is grasped in the right hand and is used for picking the strings at a point over the recess portion 29. In playing the instrument, only the center "G" string and the near "B" strings are picked. A left-handed person may place the instrument 7 across the lap in the opposite direction so that the right hand may be used with the match stem, not shown, for noting the strings and the left hand used with the plectrum 32 for picking the strings, in which case the other or near "B" string 24 would be employed with the center "G" string 23.

The plectrum 32 is preferably formed from an animal horn or from material of a similar nature.

Various modifications and changes are contemplated and may obviously be resorted to, without departing from the spirit and scope of the in-

vention as hereinafter defined by the appended claim.

I claim:

In a stringed musical instrument, a finger board adapted to extend from end-to-end of an elongated sounding box and supported thereby and disposed thereabove, said finger board having string supporting bridges rising therefrom adjacent each end thereof, a plurality of 10 standing frets rising from said finger board and located between said bridges, said frets being disposed transversely of the finger board in longitudinally spaced relationship to one another from adjacent one end of the finger board and terminating a distance from the other end thereof, the upper surface of said finger board being provided with a concave portion located adjacent the last mentioned end thereof and between the bridge at said end and the adjacent fret of the finger board and the upper surface of said finger board being inclined upwardly and away from the upper surface of the sounding box from said concave part to the first mentioned end of the finger board.

ARTHUR HORDEN KIMMONS.
